UNITED STATES PATENT OFFICE

RICHARD M. HEAMES, OF GROSSE POINTE, AND BIRGER W. LINDQUIST AND HAROLD STARK, OF DETROIT, MICHIGAN

APPARATUS FOR HEAT TREATING

Application filed June 2, 1927. Serial No. 195,986.

The invention relates in general to improvements in the art of heat treating objects such as metallic bodies, and relates more specifically to an improved process of and apparatus for treating relatively small metal articles such as nuts, washers, bolts, screws or the like, by application of heat, in order to alter certain characteristics of the said articles.

10 A general object of the invention is to provide a new and useful process of heat treating a series of metal articles in a manner which will insure uniformity in the characteristics of the finally treated articles.

15 Another general object of the invention is to provide simple, compact, durable and highly efficient apparatus for effecting commercial exploitation of the improved process.

Some of the more specific objects and advantages of the improvement are as follows:—

I. To provide an improved method of uniformly heat treating relatively small metal objects in succession for the purpose of hardening, annealing, changing the chemical analysis, or changing some other characteristic of the objects.

II. To provide an improved process of automatically handling relatively delicate metallic articles in quantity and while in highly heated condition, without in any manner damaging the individual articles.

III. To provide an improved process of effectively carburizing or case hardening metal alloy bodies, and especially bodies formed of steel.

IV. To provide improved apparatus for transporting a succession of relatively small objects through a treating zone wherein the 40 temperatures exceed 300° F.

V. To provide an improved conveyor especially adapted to withstand relatively high temperatures, for transporting objects in succession through a heat treating zone.

45 VI. To provide heat treating apparatus capable of conducting the objects to be treated through a heat treating zone in the form of a relatively thin layer, either openly or in confined condition, as desired.

VII. To provide mechanism for gradually

and gently conveying objects such as screws and bolts in quantity and in spaced relations to each other, toward, through and from a heat treating zone.

VIII. To provide other improvements in the art of heat treatment and in the details of construction and operation of heat treating apparatus, whereby metallic bodies may be uniformly treated in quantity and at minimum cost.

These and other objects and advantages of the improvement will be apparent from the following description.

A clear conception of the various steps of the improved process and of the details of construction and operation of several embodiments of apparatus adapted to commercially exploit the said process, may be had by referring to the drawings accompanying and forming a part of this specification in which like reference characters designate the same or similar parts in the various views.

Fig. 1 is a side elevation of an improved hardening or annealing furnace for heat treating a succession of relatively small metallic bodies or objects.

Fig. 2 is a top view of the improved hardening or annealing furnace, of Fig. 1.

Fig. 3 is an enlarged transverse section through the heating zone or chamber of the 80 heat treating furnace shown in Fig. 1.

Fig. 4 is an enlarged transverse section through the loading portion of the heat treating apparatus.

Fig. 5 is an enlarged transverse section 85 through the heat treating apparatus, the section being taken in the vertical plane of the axis of the tensioning drum.

Fig. 6 is a fragmentary enlarged sectional view through the discharge end of the furnace showing the details of construction of the tensioning roller.

Fig. 7 is a side elevation of a modified type of heat treating furnace especially adapted for case hardening metallic bodies.

Fig. 8 is an enlarged transverse section 95 through the heating zone or chamber of the heat treating furnace shown in Fig. 7.

Fig. 9 is an enlarged fragmentary top view of the endless metal ribbon or element. 100

Fig. 10 is an enlarged transverse section through the endless metal ribbon or element. The improved heat treating apparatus comprises in general an endless conveyor ribbon or element 2 having upper and lower horizontal stretches and looped ends which coact with driving and tension drums 10, 11, respectively. The loading portion of the upper or active stretch of the ribbon 2 is supported upon a series of rollers 20 and is longitudinally movable between stationary guides 5, in front of the heating chamber 6. Loading pans 3, 4 normally containing a supply of the work or objects to be treated, may be positioned on opposite sides of the element 2 adjacent to the guides 5. The heating chamber 6 is of tunnel-like form and has end openings through which the upper stretch or run of the conveyor 2 extends for carrying work into and out of the chamber. Extending longitudinally of the heating chamber 6 in spaced relation to the floor, roof and side walls thereof, is a refractory hearth 40 upon which the upper run of the conveyor may be supported, the hearth being supported by two longitudinally extending rows of piers 41. Extending upwardly from the sides of the hearth are walls 42, the purpose of which will presently appear. Firing into the space 35 between the bottom of the hearth and the floor of the chamber, from the sides of the heating chamber 6, are fluent fuel burners 9, the burners along one side wall being staggered with respect to the burners along the other side wall as indicated in Figs. 2 and 3. By reason of the fact that these burners are staggered as aforesaid, the hot gases projected from the burners 7 tend to flow toward the opposite side wall of the heating chamber, upwardly along the side passages between the hearth and the chamber side walls, and finally longitudinally of the chamber for exit through the end openings provided for the passage of the conveyor. This system of firing avoids initial impingement of high velocity gases against the conveyor or on the work resting thereon, but nevertheless insures thorough heating of the work by reason of the fact that the work is heated from above by the gases of combustion which circulate and flow longitudinally of the heating chamber 6 in the upper portion 36 thereof, and is further heated from below by heat which passes through the hearth and through the conveyor supported thereon. It will be further appreciated that since the hearth is formed of refractory material and is relatively massive, it will not become unduly hot even though the bottom thereof forms the top of a combustion chamber. On the other hand, it will serve as an accumulator of heat for uniformly heating the conveyor throughout its width. By extending the side walls of the hearth above the conveyor-supporting surface thereof, the upwardly rising gases of

combustion are brought into relatively close proximity to the roof of the chamber 6, with the result that as the two side streams meet in the space 36 above the hearth, they are deflected downwardly into the trough formed by the said side walls, for circulation about the work or objects on the conveyor. The delivery end of the heater 6 may be provided with a gas discharge hood 19 which maintains the high temperature for some distance beyond the discharge end of the heating chamber, and which may be connected to a chimney if desired, but this hood may be omitted.

The driving drum 10 is supported upon a shaft 24 which is mounted in bearings adjacent the discharge end of the heating chamber 6, and which is continuously rotatable by means of an electric motor 8 or the like through transmission gearing 9. A pressure roller 22 carried by swinging supports 25, is resiliently urged against the element 2 adjacent to the drum 10, by means of springs 26, as shown in Fig. 6, and serves to maintain effective driving engagement between the drum 10 and the metal ribbon. The tension drum 11 is rotatably supported upon a movable support or carriage 12 having wheels 13 cooperating with guide rails 14. The carriage 12 together with the drum 11, are constantly urged in a direction away from the driving drum 10, by means of a weight 16 which is connected to the carriage 12 through chains cooperating with idler sheaves 15 as shown in Figs. 1 and 4. The lower or return stretch of the element 2 may also be supported by means of a guide plate 23 in order to prevent excessive sagging thereof.

Located below the discharge end of the conveyor ribbon or element 2, is a cooling tank 18 which may be supplied with a suitable cooling medium such as oil or water. A final discharge conveyor specifically illustrated in the form of an endless elevating screen 17 is adapted to deliver the treated objects from the tank 18, and may be driven by the motor 8 in an obvious manner.

The improved heat treating apparatus specifically disclosed in Figs. 7 and 8, is of the same general construction as that shown in Figs. 1 to 6 inclusive, but is additionally provided with means for confining the objects in a layer of other material such as pulverized carbon 33, during the heating operation. The confining means consists of a second endless element or belt 27, formed of metal, and supported above the conveyor element 2 by means of end drums 29 and rollers 34. The belt 27 may be driven either positively or by the element 2 acting through the intervening layer of material 33, and is provided with side walls 28 for confining the material 33 as shown in Fig. 8. The delivery end of the modified type of heat treat-

ing apparatus, is preferably provided with a screen 30 or similar means for separating the treated objects from the confining material, the separating screen being adapted to deliver the removed objects to a cooling basin or tank 32, and to discharge the confining material to a discharge chute 31. The separating screen 30 may obviously be made of any desired length and so disposed to effectively 10 accomplish its purpose, and may be either stationary or vibratory.

The material employed in the formation of the endless elements 2 and 27 is an important feature of the present invention, and must be capable of effectively resisting temperatures above 300° F., and preferably above 15 1300° F., without destruction or corrosion. It has been found that so-called "stainless" steel, that is, steel containing in excess of 20 15% of chromium and a relatively small quantity of carbon, will effectively meet said requirements. Other alloy steels which are heat resistant at high temperatures and which are not subject to corrosion by furnace gases, 25 may also be used. The elements 2 and 27 are formed of relatively thin sheet metal in order to provide the desired flexibility at the looped ends of the conveyor, and the conveyor element 2 should preferably be provided with 30 means associated with the opposite side edges thereof, for retaining the objects thereon. As specifically disclosed in Figs. 9 and 10, the endless element 2 is provided with series of integral outwardly extending projections 35 21 stamped out of the body of the ribbon, thus producing a ridge along each of the longitudinal edges of the ribbon. These projections 21 extending upwardly from the object supporting side of the belt 2, provide 40 barriers which serve to retain the objects upon the belt without hindering free flexing of the metal band. By forming the projections 21 integral with the band, the cost of manufacture is reduced to a minimum, while 45 maximum belt strength is retained. In order to obviate possible cracking of the metal belt due to the formation of square cornered slots therein, the outer ends of the punched projections 21 are preferably rounded as shown in 50 Fig. 9.

By reason of the fact that the endless elements 2 and 27 are thin and flexible, the cost and difficulties of replacement are reduced to a minimum. Thus while the steel entering 55 into the composition of said elements, may be relatively more expensive, weight for weight, than a steel such as would ordinarily be suitable for a relatively heavy jointed or articulated conveyor, nevertheless on account of 60 said elements being thin enough to be flexible, the cost of the steel entering into the conveyor is a minor factor. Furthermore, because of the fact that the conveyor is not an articulated affair but is made from a flat 65 strip of material, it will be readily appre-

ciated that the cost of fabrication thereof, is reduced to a minimum. Aside from the simple operation of joining the ends of the strip to form an endless member, and of forming the side projections thereon, the strip may be used as it is produced in the steel mills. The continuity of the surface presented by the ribbon or strip forming the conveyor, also prevents relatively small objects from lodging in or falling through openings such as may exist in a jointed or articulated conveyor, at the unions between the successive members. It will be further appreciated that replacement of the improved conveyor elements in a furnace, is a relatively simple operation on account of the fact that these elements are relatively light and may therefore be easily handled. Another very important result flowing from the use of a thin 70 75 80 85 90 95 100 105 110 115 120 125 130 endless element 2 and 27, is that the heat absorbed by and carried out of the heating chamber 6 by such an element, is reduced to a minimum.

During normal operation of the apparatus disclosed in Figs. 1 to 6 inclusive, in the commercial exploitation of the improved process for the purpose of merely hardening a series of relatively small metallic bodies or objects in succession, the combustion chamber 35 and upper chamber portion 36 are in highly heated condition by virtue of the fuel burned in the combustion chamber, and one or both of the pans 3, 4 are supplied with the objects to be treated. The endless ribbon or element 2 is being constantly advanced by operation 100 of the motor 8, the gearing 9 and the driving drum 10, and the tensioning drum 11 is functioning to maintain the ribbon in taut condition. With the machine elements thus in action, an attendant removes the objects from the pans 3, 4 and carefully arranges them in the form of a substantially continuous thin layer upon the advancing loading portion of the element 2 between the guides 5. If the objects are relatively heavy or of delicate 110 construction, thus making them subject to injury when subjected to impact while in highly heated condition, the attendant should see to it that the objects are arranged in segregated order so that impact therebetween is 115 avoided during delivery of the objects from the element 2 to the cooling bath. If the objects are light or of sturdier structure, this precaution need not be taken, although the thin layer formation should be maintained 120 regardless of the specific characteristic of the objects. After the objects have been thus properly loaded, they are carried through the heating zone wherein both the element 2 and the objects resting thereon are gradually and 125 uniformly heated to temperatures ranging from 800° F. to 2500° F. or higher, depending upon the specific characteristics of the work being treated. Upon leaving the heating zone, the successive heated objects are de- 130

livered by gravity from the discharge end of the element 2 directly into the cooling tank 18 wherein the objects are quickly cooled and effectively hardened. The hardened objects are subsequently delivered from the tank 18 and from the liquid therein by means of the elevating screen 17.

When the objects have been thus hardened, they may subsequently be annealed or properly tempered, by passing them through a similar heat treating device wherein the heating zone is not as highly heated as in the hardening furnace and wherein final cooling is effected in accordance with the final results desired. In some instances no final cooling may be desired, whereas in other cases a final quench of oil, water or other liquid may be necessary. While the objects are likewise arranged in the form of a thin layer while passing through the annealing furnace, in order to insure uniformity in the treatment thereof, they need not, on account of the previous hardening, be subjected to the same care in arranging them upon the element 2, that was required during the hardening operation.

During normal operation of the apparatus disclosed in Figs. 7 and 8, in the commercial exploitation of the improved process for the purpose of case hardening or carburizing metallic objects, the endless element 2 is being constantly advanced as previously described, and the belt 27 is likewise being constantly advanced about the drums 29. One of the pans 3, 4 may be supplied with the objects to be treated, and the other with the imbedding material or carbon 33. The operator after arranging the objects upon the element 2 as heretofore described, sprinkles the carbon 33 over the objects thus embedding the successive objects and producing a relatively thin strip of carbon with the objects concealed therein. This strip of material is encased between the elements 2 and 27 and the side walls 28, during its passage through the heating zone, thus permitting the applied heat to effectively case harden the confined objects by application of heat through the carbon. The heat thus applied to the carburizing compound, generates gases which are retained in contact with the objects at sufficiently high temperature to cause the objects to absorb the carbon contained in the gases, thus effecting so-called "case hardening". Upon delivery of the carbon strip from the furnace, the separating screen upon which the carbon and the objects are deposited by gravity, becomes effective to segregate the objects from the carbon in an obvious manner, whereupon the objects may be cooled and delivered from the apparatus.

From the foregoing description it will be apparent that with the improved process and apparatus, the objects may be uniformly heat treated in succession for the purpose of either hardening, annealing or otherwise changing

a characteristic thereof, without danger of damaging the individual objects. The modified apparatus of Figs 7 and 8 permits effective and continuous carburizing of the objects, and both forms of apparatus will obviously treat large quantities of material at relatively low cost. The improved endless conveyor is adapted to effectively withstand the high temperatures to which it is subjected, without deterioration, and the driving and tensioning devices function to continuously advance the metal ribbon without slippage. While the conveyor disclosed herein consists of a single thin continuous ribbon of metal, it will be apparent that the term "endless conveyor" is intended to include any element or series of elements adapted to present an uninterrupted supporting surface for the objects within the heating chamber. The conveyor plate should however be relatively resistant to corrosion under high temperature, and if a single plate is used, the material must be sufficiently ductile to bend without fracturing when flexing about relatively small supporting drums or pulleys. The entire apparatus is relatively simple and rigid in construction, and is also extremely compact when the results accomplished are considered.

It should be understood that it is not desired to limit the invention to the exact steps of the improved process or to the precise details of construction of the apparatus herein described, for various modifications within the scope of the claims may occur to persons skilled in the art.

It is claimed and desired to secure by Letters Patent:—

1. In combination, means forming a movable stretch of ribbon for supporting a series of objects, means for confining the successive objects upon said stretch in the form of a thin layer, and means for heating the said objects while thus confined.

2. In combination, means forming a stretch of ribbon for supporting objects in relatively spaced relation and in the form of a thin layer, means for confining the objects upon said stretch, means for subjecting the objects to gradually increasing temperatures while supported upon said stretch, and means for subsequently suddenly cooling the objects upon delivery thereof from said stretch.

3. In a heat treating furnace, means forming a heating zone, a conveyor comprising thin metal plate movable directly through said zone and presenting a continuous supporting surface for exposing to said zone objects carried by said surface, and means carried by said plate to prevent objects from rolling laterally from said conveyor.

4. In a heat treating furnace, means forming a heating zone, a conveyor comprising a single thin metal ribbon movable directly through said zone and presenting a continu-

ous supporting surface for exposing to said zone objects resting upon and carried by said ribbon, and means movable with said ribbon to prevent objects from rolling laterally therefrom.

5. In a heat treating furnace, the combination of means forming a heating chamber, a hearth in spaced relation to the floor of said chamber, a material conveyor comprising an endless thin metallic band having its upper run supported on said hearth and having its lower run on the exterior and beneath the floor of said chamber, and means for heating said hearth from below.

15. 6. In a heat treating furnace, the combination of means forming an elongated heating chamber, a fixed hearth extending longitudinally of the chamber in spaced relation to the floor, roof and side walls of said chamber, and a movable hearth comprising an endless thin metallic band one run of which is supported by and movable over the fixed hearth and the other of which is on the outside and beneath the floor of said chamber, and means 25 for introducing burning gases below the hearth for circulation within said chamber.

7. In a heat treating furnace, means forming a heating chamber, an imperforate refractory hearth spaced from the floor of said chamber and having a depression forming refractory walls extending along the upper side portions of said hearth, a conveyor movable along said hearth within said depression and between said walls, and means for circulating hot gases from beneath said hearth over said walls and along objects being transported by said conveyor.

40. 8. In a heat treating furnace, means forming a heating chamber, a hearth extending longitudinally within said chamber and having longitudinal refractory side walls forming a depression at the top of said hearth, a conveyor movable longitudinally within said depression, and means for circulating hot gases laterally over said walls and longitudinally of said depression.

9. In combination, means forming a continuous support for objects to be treated, means for confining objects embedded within 50 in carburizing material in the form of a thin layer upon said support, means for heating said objects and material while thus confined, and means for finally separating the treated objects from the material.

55. 10. In a heat treating furnace, means forming a heating zone, a conveyor comprising a thin metal plate movable through said zone and presenting a continuous medial supporting surface for exposing to said zone objects resting upon and carried by said plate, and movable means at the sides of said plate for preventing objects from leaving the carrying surface of said plate.

60. 11. In a heat treating furnace, means forming a heating zone, and a conveyor comprising

ing thin metal plate movable through said zone and presenting a continuous supporting surface for exposing to said zone objects carried by said surface, the opposite edges of said plate being provided with upstanding integral projections for preventing objects from rolling laterally from said conveyor.

12. In a heat treating furnace, means forming loading and heating zones, a conveyor comprising a thin metal ribbon movable through said zones in succession, a series of rollers providing a direct support for said ribbon at said loading zone, and a hearth providing a direct support for said ribbon at said heating zone.

13. In a heat treating furnace, means forming a heating chamber, an imperforate hearth spaced from the floor of said chamber and having upstanding refractory side walls, a conveyor comprising a thin metal ribbon movable over said hearth between said side walls, and means for circulating hot gases from beneath said hearth over said walls and along the upper surface of said ribbon.

14. In a heat treating furnace, means forming a heating chamber, a hearth spaced from the floor of said chamber and having upstanding side walls, means for circulating hot gases from beneath said hearth over said walls, and a conveyor comprising a flexible metallic belt, movable through said chamber above said hearth, said belt having upstanding integral portions at the opposite edges thereof and said side walls cooperating with said upstanding plate portions to protect the latter from said hot gases.

15. In a heat treating furnace, means forming a heating chamber, a hearth extending through said chamber and having upstanding refractory side walls disposed longitudinally thereof, means for circulating hot gases laterally over said walls, a conveyor comprising a belt movable through said chamber above said hearth and between said walls, and means movable with said belt to prevent objects from rolling laterally therefrom, said side walls cooperating with said last mentioned means to protect the latter from said hot gases.

16. In a heat treating furnace, means forming an open loading zone and a confined heating zone contiguous with said loading zone, a conveyor comprising a ribbon movable through said zones in succession, a series of rollers providing a direct support for said ribbon at said loading zone, and a stationary hearth providing a direct support for said ribbon throughout said heating zone.

17. In a heat treating furnace, means forming contiguous loading and heating zones, a periodically interrupted support located at said loading zone, a hearth presenting a continuous supporting surface within said heating zone, a conveyor comprising a ribbon movable over said support and said surface,

a rotary drum coacting with said ribbon at the egress thereof from said heating zone, a tension drum coacting with said ribbon at the ingress thereof to said loading zone, and means cooperating with said tension drum to maintain said ribbon taut while traversing said support.

18. In a heat treating furnace, means forming contiguous loading and heating zones, a series of laterally spaced rotary rollers providing a periodically interrupted anti-friction support at said loading zone, a hearth presenting a continuous supporting surface extending throughout said heating zone, a conveyor comprising a continuous ribbon having an upper stretch movable over said support and said surface, a rotary drum coacting with said ribbon at the egress thereof from said heating zone, a tension drum coacting with said ribbon at the ingress thereof to said loading zone, and means coacting with said tension drum to maintain said ribbon taut while advancing over said rollers.

19. In a heat treating furnace, means forming an open elongated loading zone and a confined elongated heating zone contiguous with said loading zone, a conveyor comprising a ribbon movable longitudinally through said zone in succession, and stationary storage pans disposed along the opposite sides of said conveyor at said loading zone.

20. The combination with a furnace having a heating zone, of a conveyor movable through said zone, said conveyor comprising a relatively stiff but longitudinally flexible band provided along each of the longitudinal edges of its object supporting side with a barrier permitting free flexing of the band.

21. The combination with a furnace having a heating zone, of a conveyor movable through said zone, said conveyor comprising a relatively stiff but longitudinally flexible band provided along each of the longitudinal edges of its object supporting side with a barrier permitting free flexing of the band, said barrier comprising a row of individual upright rigid fingers.

22. A conveyor for use in a heat treating furnace, comprising an endless metallic flexible sheet provided inwardly of its longitudinal edge with a series of relatively narrow slots and an upright projection at the end of each slot.

23. A conveyor for use in a heat treating furnace, comprising an endless metallic flexible sheet provided inwardly of its longitudinal edge with a series of relatively narrow slots and an upright projection at the end of each slot of size the same as the adjoining slot.

24. A conveyor for use in a heat treating furnace, comprising an endless metallic flexible sheet provided inwardly of its longitudinal edge with a series of relatively narrow slots each of which at its end most remote from the edge of the sheet is arcuate, and an

upright projection at the other end of each of said slots.

25. A conveyor for use in a heat treating furnace, comprising an endless metallic flexible sheet provided inwardly of its longitudinal edge with a longitudinally extending barrier for objects on the conveyor, said barrier comprising a series of relatively narrow upright projections permitting free longitudinal flexing of the conveyor.

26. A conveyor for use in a heat treating furnace, comprising an endless metallic flexible sheet provided inwardly of its longitudinal edge with a longitudinally extending barrier for objects on the conveyor, said barrier comprising a series of relatively narrow upright projections permitting free longitudinal flexing of the conveyor, and a series of slots in the sheet laterally aligned with and conforming in size to the adjoining projections.

27. The combination with a furnace having a heating zone, of a conveyor movable through said zone, said conveyor comprising an endless longitudinally flexible metallic band provided along each of its longitudinal side edges with a barrier permitting free flexing of the band while preventing objects from dropping off at said edges.

28. In a heat treating furnace, means forming a heating chamber, a hearth within said chamber, means for delivering hot gases to objects over the side edges of said hearth, and a conveyor for said objects comprising a longitudinally flexible metallic band movable through said chamber above said hearth, said band being of less width than the distance between said side hearth edges and being provided along each of its side edges with a barrier permitting free longitudinal flexing of the band while preventing objects from dropping off at said edges.

In testimony whereof, the signatures of the inventors are affixed hereto.
